(57) **CLAIM**

The ornamental design for a receptacle adapter, as shown and described.

DESCRIPTION

FIG. 1 is a front elevational view of a receptacle adapter having its covering closed;

FIG. 2 is a right side elevational view thereof having its covering closed;

FIG. 3 is a rear elevational view thereof;

FIG. 4 is a top view thereof;

FIG. 5 is a bottom view thereof; and,

FIG. 6 is a right side elevational view thereof having its covering opened.

The broken line environmental showing is for illustrative purposes only and forms no part of the claimed design.
